UNITED STATES PATENT OFFICE.

JOHN M. RE MAKER, OF SPRINGFIELD, MASSACHUSETTS.

DESIGN FOR A LAMP-SHADE STANDARD.

46,512.

Specification for Design.

Patented Oct. 6, 1914.

Application filed July 24, 1914. Serial No. 852,913. Term of patent 7 years.

To all whom it may concern:

Be it known that I, JOHN M. RE MAKER, a citizen of the United States of America, residing at Springfield, in the county of Hampden and State of Massachusetts, have invented a new, original, and ornamental Design for Lamp-Shade Standards, of which the following is a specification, reference being had to the accompanying drawing, forming a part thereof.

The figure is a perspective view of a lamp shade standard, showing my new design.

I claim:

The ornamental design for a lamp shade standard, as shown.

JOHN M. RE MAKER.

Witnesses:

F. A. CUTTER,

A. C. FAIRBANKS.
